US00D597869S

(12) **United States Design Patent**
Elias

(10) **Patent No.:** US D597,869 S
(45) **Date of Patent:** ** Aug. 11, 2009

(54) **MEASURING ELEMENT**

(76) Inventor: **Lora Elias**, 5325 Fleet Ave., Cleveland,
OH (US) 44105

(**) Term: **14 Years**

(21) Appl. No.: **29/324,676**

(22) Filed: **Sep. 17, 2008**

(51) LOC (9) Cl. **10-04**

(52) U.S. Cl. **D10/64**

(58) **Field of Classification Search** D10/64;
33/476, 494, 562-567.1, 679.1, 810

See application file for complete search history.
